CLAIM

We claim the ornamental design for a brush tub, as shown and described.

DESCRIPTION

FIG. 1 is a side elevation view of a new design for a brush tub according to the present invention;

FIG. 2 is a top plan view thereof;

FIG. 3 is a bottom plan view thereof;

FIG. 4 is an end elevational view thereof;

FIG. 5 is an end elevational view thereof, opposite to that shown in FIG. 4;

FIG. 6 is a view of an interior of the design of the brush tub taken along line 6—6 in FIG. 2; and,

FIG. 7 is a top plan view of the interior shown in FIG. 6.
